UNITED STATES PATENT OFFICE.

JAMES T. COLE, OF CHICAGO, ILLINOIS.

DESIGN FOR A WATER-COOLER.

No. 38,467.

Specification for Design.

Patented Feb. 26, 1907.

Application filed January 21, 1907. Serial No. 353,400. Term of patent 14 years.

To all whom it may concern:

Be it known that I, JAMES T. COLE, a citizen of the United States, residing at Chicago, in the county of Cook and State of Illinois, have invented a new, original, and ornamental Design for Water-Coolers, of which the following is a specification, reference being had to the accompanying drawing, forming part hereof.

The figure is a perspective view of a water-cooler, showing my new design.

I claim—

The ornamental design for a water-cooler, as shown.

JAMES T. COLE.
